Primary Examiner — Kendra Leslie Hamilton*Assistant Examiner* — Amanda Christensen(74) *Attorney, Agent, or Firm* — Andrew F. Young, Esq.; Nolte Lackenbach Siegel(57) **CLAIM**

The ornamental design for a battery charger, as shown and described.

DESCRIPTION

FIG. 1 is a front, top left side perspective view of a battery charger, showing our new design;

FIG. 2 is a rear, top, right side perspective view thereof;

FIG. 3 is a front elevation view thereof.

FIG. 4 is a rear perspective view thereof.

FIG. 5 is a top plan view thereof.

FIG. 6 is a bottom plan view thereof.

FIG. 7 is a left side elevation view thereof; and,

FIG. 8 is a right side elevation view thereof.

The broken lines depict portions of the battery charger that form no part of the claimed design.

1 Claim, 8 Drawing Sheets(56)
